Primary Examiner — Mark A Goodwin*Assistant Examiner* — Benjamin M Weeks(57) **CLAIM**

The ornamental design for a vehicle front headlamp, as shown and described.

DESCRIPTION

FIG. 1 is a perspective view of a vehicle front headlamp residing on a leftside of a vehicle (the rightside vehicle front headlamp being a mirror image of the leftside vehicle front headlamp);

FIG. 2 is a front view thereof;

FIG. 3 is a side view thereof; and,

FIG. 4 is a top view thereof.

The broken lines in the drawings illustrate portions of the vehicle front headlamp that form no part of the claimed design.
